UNITED STATES PATENT OFFICE.

EDWARD F. HOWE, OF WATERTOWN, MASSACHUSETTS.

DESIGN FOR A MANDOLIN-BODY.

SPECIFICATION forming part of Design No. 27,559, dated August 24, 1897.

Application filed February 18, 1897. Serial No. 624,055. Term of patent 14 years.

To all whom it may concern.

Be it known that I, EDWARD F. HOWE, a citizen of the United States, residing in Watertown, in the county of Middlesex and State of Massachusetts, have invented and produced a new and original Design for a Mandolin-Body, of which the following is a specification, reference being made to the accompanying drawings, forming a part thereof.

10 Figure 1 of the drawings shows a perspective view of my new and original design for a mandolin-body; Fig. 2, a longitudinal section on line $x-x$ of Fig. 1; and Fig. 3, a cross-section on line $y-y$, Fig. 1.

15 The leading feature of my design consists in a lute-shaped top having a longitudinal central swell.

a represents the lute-shaped top, having a hole a' and a longitudinal central swell a^2 .
 b represents a mandolin-shaped body; c , 20 the neck, having a head d , and e a bar over which the strings of the instrument pass, which are arranged in pairs.

I claim—

The design for a mandolin-body as herein 25 shown and described.

In testimony whereof I have signed my name to this specification in the presence of two subscribing witnesses.

EDWARD F. HOWE.
